(57) **CLAIM**

The ornamental design for a snow, ice and/or moisture sensor, as shown and described.

DESCRIPTION

FIG. 1 is a top perspective view of a sensor showing my new design;

FIG. 2 is a bottom perspective view thereof;

FIG. 3 is a side view thereof, the opposite side view being substantially identical;

FIG. 4 is another side view thereof;

FIG. 5 is a top view thereof; and,

FIG. 6 is a bottom view thereof.
